PRESSURE BAR AND PRESSURE BAR
HOLDER ASSEMBLY IN VENEER CUT-
TING MACHINESEricsson H. Merritt, Lockport, N. Y., assignor, by
mesne assignments, to Solem Machine Com-
pany, Rockford, Ill., a corporation of Illinois

Application August 25, 1948, Serial No. 46,084

1 Claim. (Cl. 144—213)

1

This invention relates to the art of cutting and slicing wood veneer; more particularly it relates to an improved pressure bar and pressure bar holder combination assembly to be used with veneer cutting and slicing equipment.

In general practice rotary veneer is produced by revolving a log against a knife whose length is equal to or in excess of the length of the log being cut. Sliced veneer is produced by clamping a flitch to a reciprocating table and moving the table with the flitch past the knife. At each stroke a sheet of veneer is cut from the flitch. In each of the described veneer cutting operations, to prevent the wood from splitting ahead of the knife, a pressure bar is provided to apply pressure to the log just ahead of the knife. Thus, the ribbon of veneer severed from the log by the knife is actually extruded through the slot formed by the knife and the pressure bar. The cross-section of this slot is slightly less than the thickness of veneer being cut. To cut smooth uniform thickness veneer, the slot must be of uniform cross-section and have parallel edges. Furthermore, in the case of rotary veneer the bottom edge of the slot formed by the edge of the knife must be in accurate parallel relationship to the axis of rotation of the log and the top of the slot formed by the pressure bar must be in accurate parallel relationship to the knife edge. Since it is not unusual to cut veneer as thin as fifteen-thousandths of an inch in thickness, it is obvious that the tolerances to which the pressure bar must be set, are extremely narrow.

Pressure bars generally vary in size from $\frac{1}{2}$ inch to $\frac{3}{4}$ inch thick, usually $\frac{1}{2}$ inch to 2 inches wide when new, and varying in length from 24 inches to 200 inches. Adjusting bolts are usually provided in order that the contact edge of the pressure bar may be adjustably maintained in accurate parallel relationship with the cutting edge of the knife. Such a light steel section as the pressure bar, will, if placed on edge and supported at both ends, deflect appreciably due to its own weight alone, not to mention the loading incident to the cutting of veneer. As the pressure bar becomes narrower due to grinding, this deflection materially increases. Thus, the pressure bar itself has little inherent rigidity when considered as a beam.

Pressure bars contain a considerable amount of internal stresses. Additional stresses are built up in the edge of the pressure bar by the constant peening action of the log striking the pressure bar. This is particularly true when irregular

shaped logs are being reduced to a cylinder preliminary to the cutting of veneer. Preparatory to a grinding or sharpening operation on the pressure bar, due to the stresses introduced by the veneer cutting operation, it is necessary to force the pressure bar to assume a straight line. The bevel of the pressure bar is ground until a sharp contact edge is produced which is a straight line within the limits of accuracy of the grinder and the perfection of the plane of the face of the pressure bar. This grinding operation to a certain extent releases many of the stresses which were formed in the pressure bar during the cutting operation. When the pressure bar is released from the grinder clamps which hold the pressure bar rigidly in place during the grinding operation, it immediately assumes its natural shape and the contact edge is no longer a true straight line. Accordingly, when this pressure bar is attached to the pressure bar carriage in the veneer cutting machine, it must be adjusted to compensate for the width lost in the grinder and also it must be forced by local adjusting screws provided in the pressure bar carriage, to take such a shape that the contact edge will be a true straight line parallel to the axis of rotation of the log. This is a time consuming operation requiring a high degree of skill. Thus, according to the method as practiced heretofore of handling veneer cutting pressure bars, a precision alignment of the pressure bar is required for both the grinding operation and for the repositioning of the sharpened pressure bar in its holder on the cutting machine.

It is an object of this invention to provide a pressure bar and pressure bar holder assembly which facilitates the positioning of the pressure bar in a veneer cutting machine so that precision alignment is obtained with a minimum amount of local adjusting.

Another object of this invention is to provide a pressure bar and pressure bar holder assembly which pressure bar, when precision ground, will be in perfect alignment without further adjustment when placed in the veneer cutting machine.

It is also an object of this invention to provide an improved pressure bar and pressure bar holder assembly for a veneer cutting machine which eliminates all but a small fraction of the time required to change a pressure bar in a veneer lathe or a veneer slicer.

Further objects will become apparent from the description of the invention and the claims.

These objects are accomplished by means of the applicant's invention herein described, which

provides an accurately machined rigid steel beam, called the holder, to which a pressure bar is adjustably attached. The holder is so constructed as to have a moment of inertia sufficiently great to resist deflection of the pressure bar caused by unbalanced stresses therein. The pressure bar and pressure bar holder are removable as a unit from the veneer cutting machine. Threaded holes are provided in the holder whereby the pressure bar may be securely held thereto. Push and pull adjusting screws are also provided for in the holder to facilitate adjustment of the pressure bar in the holder. The machined surfaces of the holder and their cooperative machined surfaces on the veneer cutting machine are so constructed as to maintain a fixed relationship between the surfaces and the line of contact between the contact edge of the pressure bar and the log or flitch.

With such a construction, during the sharpening operation, the dull or nicked pressure bar, together with its holder, are removed as a unit from the lathe or the slicer. At the grinding wheel, the pressure bar is adjusted with respect to the locating surfaces on the holder to a distance equal to the amount of the pressure bar which must be ground away to produce a new perfect edge. The bevel of the pressure bar while rigidly clamped in its holder, is ground until the distance from the new edge to the locating surfaces on the holder is the correct distance to bring the pressure bar contact edge to the proper position in the veneer lathe or slicer. The pressure bar and pressure bar holder are then removed from the grinder, and, due to the sufficiently great moment of inertia of the pressure bar holder with respect to the pressure bar, or in other words, the weight of the pressure bar holder with respect to the pressure bar, the contact edge of the pressure bar remains a straight line and does not bow or otherwise deflect due to the internal stresses in the pressure bar. On replacing the resharpened pressure bar and its holder in the veneer cutting or slicing machine so that the locating surfaces of the pressure bar holder are in contact with their cooperative locating surfaces in the veneer cutting machine, the pressure bar is automatically in correct adjustment requiring no further manual local adjusting.

The invention will be more clearly understood from the following description wherein:

Figure 1 is the front elevation of a fragmentary length of the pressure bar and pressure bar holder assembly of this invention.

Figure 2 is a transverse section of the pressure bar and pressure bar holder of this invention taken on line 2-2 of Figure 1, supported in a conventional manner in a veneer lathe.

Figure 3 is a transverse section of the pressure bar and pressure bar holder of this invention taken on line 3-3 of Figure 1.

As shown in the drawings pressure bar holder 4 is an accurately machined rigid steel beam. Surfaces 5, 6, and 7 of the pressure bar holder 4 and the cooperative abutting surfaces of the pressure bar holder carriage 8 are accurately machined in parallelism so that their entire length is parallel to the axis of rotation of the log 9 in a veneer cutting lathe. The pressure bar holder 4 is equipped with a plurality of holes 10 each of which accommodates a bolt 11. Bolt 11 is so threaded so as to be bolted to the internally and externally threaded bushing 12 which is rigidly fixed in pressure bar holder carriage 8. Bolt 11 also is equipped with head 13 so constructed to

accommodate an Allen wrench whereby the entire pressure bar holder 4 is securely fastened to the pressure bar holder carriage 8. Pressure bar 14 is also adjustably attached to pressure bar holder 4 by means of a plurality of pull bolts 15 alternating with push bolts 16. Pressure bar 14 is also rigidly held in place in pressure bar holder 4 by means of push bolts 17. The entire pressure bar and pressure bar holder assembly is further held in place by end bolts 18.

In operation, log 9 is rotated against a veneer cutting knife 19 cutting a sheet of veneer which is extruded through the slot 20 one side of which is formed by the knife edge 21 and the other side of which is formed by the edge of pressure bar 14, held in place by pressure bar holder 4. On requiring resharpening, the pressure bar and pressure bar holder assembly is removed from the pressure bar holder carriage 8 by loosening bolt 11 thereby forcing the pressure bar and pressure bar holder as a unit from the pressure bar holder carriage. The pressure bar and pressure bar holder can then be taken as a unit to the grinding wheel for grinding. At the grinding wheel, bolts 17 are loosened and by means of bolts 15 and 16 the pressure bar 14 is so adjusted and ground until the contact edge of pressure bar 14 is a true straight line and in parallelism with and at a predetermined distance from the locating surfaces 5 or 7 of the pressure bar holder. Inasmuch as the pressure bar holder 4 has a sufficient moment of inertia to resist deflections of the pressure bar 14 due to stresses and strains set up in the pressure bar during the cutting and grinding operations, when the pressure bar holder which has been accurately aligned at the grinding operation is repositioned in the lathe, no further adjustment of pressure bar 14 is required. Therefore, since the distance from the contact edge of pressure bar 14 to locating surfaces 5 or 7 on the pressure bar holder is constant, and since this distance is accurately set in the grinding operation, and since these locating surfaces on the pressure bar holder have accurately machined cooperative surfaces on the pressure bar holder carriage 8, all that remains after the grinding operation is merely the seating of the pressure bar and pressure bar holder assembly in the veneer lathe. Thus, instead of the procedure as practiced heretofore of requiring two accurate alignments of the pressure bar, one during the grinding operation and another during the seating of the sharpened pressure bar in the lathe, only one alignment is necessary with the applicant's invention greatly reducing the requirements of highly skilled techniques.

According to heretofore practiced techniques, a dull or nicked veneer pressure bar requiring resharpening is removed singly from the cutting machine. An experienced grinder then grinds or resharpenes the pressure bar forcing the pressure bar, by local adjustment, to assume a true straight line. The grinder then releases the pressure bar from the grinder carriage and returns the pressure bar to the slicer or veneer lathe. However, on releasing the pressure bar from the grinder, due to unbalanced stresses in the pressure bar and its lack of rigidity, the true straight contact edge is lost due to deflections. Consequently, when this pressure bar is again positioned in the cutting lathe or slicer, realignment by local adjustment of the pressure bar is again necessary to force the contact of the pressure bar into a true straight line. Such an aligning and adjusting operation requires a skilled craftsman.

With the pressure bar and pressure bar holder assembly of this invention, it is this second local adjustment of the pressure bar that is eliminated. Inasmuch as the contact edge has been properly aligned during the grinding operation and is rigidly held in place by a holder that has a sufficient moment of inertia to resist subsequent deflections of the pressure bar and that such holder is so constructed with regard to the veneer cutting machine as to maintain a fixed relationship between the line of contact of the contact edge of the pressure bar and the log or flitch, further adjustment of the pressure bar is unnecessary when the pressure bar and its holder is repositioned in the veneer cutting machine.

What is claimed is:

In a veneer cutting machine comprising an elongated pressure bar holder carriage, the improvement which consists in the provision of a combination pressure bar and pressure bar holder assembly of elongated form removable as a unit from the carriage, said holder being relatively large in cross-section in relation to said pressure bar and having accurately machined locating surfaces adapted to abut accurately machined locating surfaces on the carriage to in-

sure close parallelism of the holder to the veneer cutting knife of the machine, push bolts adjustably threaded in the holder behind and abutting the bar at longitudinally spaced points for local 5 adjustments of longitudinally spaced portions of the bar in the plane thereof, pull bolts in a plane parallel to the plane of the push bolts supported in holes provided in the holder and threaded in holes provided in the bar for local adjustments of 10 longitudinally spaced portions of the bar in the plane thereof in the opposite direction to that of the adjustments afforded by said push bolts and other bolts rigidly securing the holder to the carriage.
